LIGHTER

Charles F. Larsen, Brooklyn, and George
McCormick, New York, N. Y.

Application November 22, 1938, Serial No. 241,772

4 Claims. (Cl. 67—7.1)

This invention relates to lighters and has for an object to provide a construction wherein the lighting elements will be caused to quickly function without any predetermined effort on the part of the operator.

Another object of the invention is to provide an improved lighter wherein the parts are moved at any desired speed to a given position and then a resistance presented so that an extra pressure will 10 quickly move the parts to a completed position and thereby give the serrated wheel of the device a sudden quick movement.

A further object of the invention is to provide an improved construction which will quickly and 15 automatically ignite a wick when actuated and quickly put out or snuff the wick when released.

In the accompanying drawing—

Fig. 1 is a longitudinal vertical sectional view through a lighter embodying the invention, certain parts being shown in elevation;

Fig. 2 is a sectional view through Fig. 1 approximately on the line 2—2;

Fig. 3 is a sectional view through Fig. 2 approximately on the line 3—3 but showing only a portion of the device illustrated in Fig. 1;

Fig. 4 is a transverse sectional view through Fig. 1 approximately on the line 4—4;

Fig. 5 is a fragmentary sectional view through Fig. 1 approximately on the line 5—5;

Fig. 6 is a fragmentary transverse sectional view through Fig. 1 on the line 6—6;

Fig. 7 is a perspective view on a reduced scale of the housing or casing shown in Fig. 1.

Referring to the accompanying drawing by numerals, 1 indicates a housing or casing which is bent or stamped from sheet metal. The respective edges 2 and 3 are held together by rivets 4 and 5 which also act to perform other functions as heretofore fully described. The casing 1 is provided with suitable air vents 6 so as to provide the proper amount of air to support combustion when the wick 7 is ignited. The wick 7 extends from the usual fluid container 8 and is correctly positioned to receive the spark when the device is functioning.

In regard to the rivet 5 it acts as a journal pin for a swinging cap 9. This cap functions also to actuate the serrated wheel 10 and the snuffer 11 which is rigidly secured thereto in position to fit over the wick 7 when the device is not functioning, as clearly shown in Fig. 1. The serrated wheel 10 is rotatably mounted on the rivet or pin 5 and is provided with the usual abutments 12 which are adapted to be engaged by respective resilient arms 13 and 14 so as to rotate the wheel

when these arms are moved in one direction. It will be observed that these arms are an integral part of the plate 15 which is journaled on the pin or rivet 5 and is provided with extensions 16 and 17 bearing against the cap 9 so that the plate and arms will move with the cap. When the arms are moved clockwise as shown in Fig. 1 they will also move the wheel 10, but when moved counter-clockwise the arms will resiliently pass over the abutments 12.

Associated with the serrated wheel 10 is a flint 18 which is slidably mounted in a tubular collar 19 and pressed by a spring 20 so as always to properly engage the serrated wheel 10. A knob 21 is secured to the cap 9 and is adapted to be pressed in a direction to the right, as shown in Figs. 1 and 3, when it is desired to ignite the wick 7. The slow movement of the parts causes the wheel 10 to rub against the flint 18 but usually will not provide a sufficient spark to ignite the wick 7. It is desirable to swing the cap to a partially open position and then to quickly rotate the wheel 10 to give a large spark so that the wick 7 will be ignited on each operation. To ensure this result a special construction has been provided.

It will be observed that an elongated abutment 22 is secured to the side member 23 of the end of cap 9, while a pin 24 is connected to the opposite side member 25. Preferably the cap is made from a single piece of pressed metal having a back, two sides and an end. The two sides adjacent the knob 21 are rounded to form the members 23 and 25. A lever 26 is pivotally mounted on pin 4, as shown in Fig. 1, and is continually pressed by a spring 27 which acts against a shoulder 28 and against a wall of housing 29 so as to cause the lever 26 a continuous tendency to move to the right, as shown in Fig. 1, to continually press against the abutment 22. Therefore, when the abutment 22 has been moved over to the left, as shown in dotted lines in Fig. 1, and then released the lever 26 will quickly move the parts back to the position shown in Fig. 1. However, when the knob 21 is pressed clockwise, as shown in Figs. 1 and 2, the pin 24 connected to the side plate 25 will engage a spring pressed swinging abutment 30 at the point or shoulder 31 and force the same to the left, as shown in Fig. 1. The abutment 30 is pivotally mounted at 32 on the arm 33 of a bell crank lever 34, which lever is pivotally mounted on pin 34' carried by housing 29. The opposite arm 35 of the bell crank lever is pressed by a spring 36 so as to remain normally in the position shown in Fig. 1. A spring 37 is connected

at 38 to the bell crank lever 34 and at 39 to a small extension from the abutment 30. The spring 37 attempts to keep the abutment 38 pressing against the point or shoulder 40 of the bell crank lever 34. When the knob 21 is moved clockwise, the pin 24 strikes the shoulder 31 and this shoulder, acting through the bell crank lever and spring just described, will resist further movement. However, if a harder push is given 10 to the knob 21, spring 36 will quickly move and the abutment 30 will move out of the way of pin 24 so that the parts will give the wheel 18 a quick partial movement and thereby produce a good spark. This spark occurs after the snuffer 11 has been moved off the wick 7. After the knob 21 has been moved to the right as far as possible, as shown in Fig. 1, it together with the cap 9 and associated parts will move under the action of arms or levers 26, back to the position 20 shown in Fig. 1 ready for a second operation. Abutment 30 and bell crank lever 34 will also quickly move back to their former positions under the action of their respective springs. When the pin 24 moves backward the abutment 38 swings away from the point or abutment 40 and allows pin 24 to pass, after which it resumes the position shown in Fig. 1 ready to function as just described.

It will be seen, therefore, that the first movement of knob 21 and cap 9 will merely uncover the wick 7 and the second quick movement will produce the spark. The abutment 22 during the first movement will move the upper end of lever 26 and during this time the snuffer 11 has been elevated until the wick 7 is completely free so that as the lever 26, pin 24 and associated parts move over to their extreme positions the wick will be exposed ready to be ignited.

In regard to the abutment 22, it will be seen 40 that the same is elongated with half-round ends and connecting flat sides. As shown in Fig. 1, the major axis is arranged substantially radial with the end of the lever 26 normally pressing against the inner end. When the cap 9 is 45 moved to its extreme position to the right, as shown in Fig. 1, the abutment will change its position relative to the lever 26, so that the outer end will be bearing against the lever whereby an extra movement of the cap 9 is secured with 50 a continuous pressure of lever 26 against the abutment to permit the spring-pressed lever 26 to quickly return the cap when released.

We claim:

1. A lighter of the character described including a casing, a fluid container having a wick, a cap for the casing, means for supporting a flint near said wick, a serrated wheel actuated by said cap for causing said flint to function to produce a spark, and means coacting with said cap for causing an operator to open the cap for part of its movement and then quickly for the remaining part, whereby said serrated wheel will be quickly moved to produce in connection with the flint an ample spark for igniting said wick, said means including a hand actuated knob and an abutment extending from said cap, a spring-pressed lever moved by said abutment against the spring acting on the lever, a pin carried by said

lever and a spring-pressed pivotally mounted abutment having a corner normally resting against said pin for resisting movement by said pin.

2. In a lighter of the character described, a cap, a serrated wheel actuated by said cap, a flint adapted to be struck by said serrated wheel, and means for causing said cap and serrated wheel to move quickly, said means including a pin carried by the cap, a pivotally mounted spring-held abutment for resisting the movement of said pin, a bell crank swingably supporting said pivotally mounted abutment and a spring acting on the bell crank for normally preventing said pivotally mounted abutment from moving out of the way of said pin whereby when sufficient pressure is brought to bear on said pin the bell crank lever will swing out of the way and thereby allow a quick movement of the pin, serrated wheel, and associated parts.

3. In a lighter of the character described, a flint, a serrated wheel, means for moving the serrated wheel in one direction manually, said means including a cap, a spring-pressed arm for moving said cap back to its former position, a pin carried by said cap, a spring-pressed pivotally mounted abutment arranged in the path of movement of said pin, and a spring-pressed bell crank lever pivotally supporting said pivotally mounted abutment, whereby when sufficient pressure is brought to bear against said pivotally mounted abutment by said pin, the bell crank lever will move downwardly and swing the pivotally mounted abutment out of the path of the pin so as to allow a quick movement of the serrated wheel, said spring-pressed pivotally mounted abutment being adapted to be swung out of the way by said pin as it moves back to its first position.

4. An automatic self-closing lighter including a casing, a fluid container having a wick, a sparking device for igniting said wick, a one-piece cap normally covering one end of said casing, means actuated by said cap upon opening for causing said sparking device to function when the cap is moved to an open position, and means presenting a temporary resistance to the opening movement of said cap, said means not functioning on the return movement of the cap so that the return movement will be continuous and smooth, said means including an abutment carried by said cap, a pivotally mounted lever swung in one direction by said abutment when said cap is actuated to produce a spark, a spring normally resisting movement of said abutment, a pin carried by said lever, a pivotally mounted bell crank lever, a spring for normally holding said bell crank lever in a given position, said bell crank lever having an offset end providing a shoulder, a spring-pressed abutment pivotally mounted on said offset end, a spring acting on said spring-pressed abutment for resiliently holding the same against said shoulder, whereby when said pin moves a predetermined distance said bell crank lever will move until said pin can pass said spring-pressed abutment.
